UNITED STATES PATENT OFFICE.

JAMES A. TODD, OF ATTALLA, ALABAMA, ASSIGNOR TO COMPRESS BUCKLE COMPANY,
OF FORT WORTH, TEXAS, A CORPORATION OF TEXAS.

BALE-TIE BUCKLE.

Application filed May 10, 1926. Serial No. 108,001.

My invention relates to bale tie buckles of the type utilized for securing the ties or bands applied to bales of cotton, jute and other baled goods.

5 More particularly, my invention contemplates certain improvements in the type of bale tie buckle forming the subject matter of Letters Patent No. 1,192,817, issued to R. L. Horsley on Jan. 25th, 1916, in which 10 is shown a buckle formed of bent wire having the ends forming the entering or open end of the buckle bent to diverge oppositely from the plane of the buckle and inclined towards the closed end of the buckle. When 15 the bale band is applied to buckles of this type the free buckle ends are both drawn together into alignment in the plane of the buckle and bent down at right angles to the buckle sides, this bending action of the 20 ends being accompanied by a slight expansion of the side walls of the buckle adjacent to its open end until they become parallel.

In the practical utilization of this buckle it has been found that when the ends of 25 the buckle are drawn into alignment under full tension of the band the frictional engagement of the free ends of the buckle on the band practically disappears.

I have conceived that the holding capacity of the buckle can be materially increased 30 if its free ends are made slightly longer so that in closed or operating position with the buckle sides parallel they cannot be drawn into alignment or into the plane of the 35 buckle but will overlap and thus provide divergent points or edges opposite the center of the band which under tension will become deformed and thus I very greatly increase the binding action of the buckle 40 on the band and its holding capacity.

My invention will be more clearly understood by reference to the accompanying specification and claims, and to the drawings forming part of this specification and in 45 which only the preferred embodiment of my invention is shown.

In the drawings:—

Fig. 1 is a plan view of the buckle, before the band is applied, the band being shown 50 in preliminary position in dotted lines.

Fig. 2 is an end of Fig. 1.

Fig. 3 shows the tie buckle in plan with the band under full tension in operating position with the buckle sides spread into

parallelism and with the bale band broken 55 away to show the buckle in full view.

Fig. 4 is a cross-sectional view taken on the line 4—4 of Fig. 3, and showing the overlapping operating position of the buckle 60 ends.

Fig. 5 is a perspective view of the buckle. Similar reference numerals refer to similar parts throughout the drawings.

In the embodiment of my invention illustrated I show a buckle formed of a single piece of metal wire which is bent to form the closed end 1 of the buckle, the slightly convergent sides 2 and 3 of the buckle, and the inturned ends 4 and 5, which together form what is termed the open end of the buckle. 70 Preferably, the ends 4 and 5, as originally formed, are bent slightly towards the closed end 1 and they are also bent to diverge oppositely from the plane of the buckle, as will be seen more clearly in Fig. 2. The ends 4 and 5 are made sufficiently long so that, as viewed in plan (see Fig. 1), they will overlap, the overlap being greater in extent than extent of convergence of the side walls from 75 parallel position. This structural feature is important, because it permits the buckle when in service, as shown in Fig. 3, to have its ends 5 and 4 bent into a plane at right angles to its side walls 3 and 2 when spread apart into parallelism, and to have the 80 free ends 4 and 5 drawn into position by the loop of the bale band 6 until they overlap just sufficiently to prevent them coming into alignment. The maintaining of this overlapping of the ends, as will be better understood by reference to Fig. 4, is important in 85 that it deforms the bite of the band, causing its center to bulge out and forcing the lapped ends of the buckle to indent themselves into 90 the band and thus to very greatly increase 95 the buckle's grip on the band and the holding capacity of the buckle. Moreover, this deformation of the band makes possible the use of the metal in the band to prevent the tendency of lapped ends to pull apart and 100 the side walls to spread apart, which if permitted will destroy the buckle. The converging side edges of the band in the bite, as will be seen very clearly in Fig. 4, will 105 actively resist any tendency of the overlapping ends 4 and 5 to pull apart and permit the walls 2 and 3 to spread beyond parallelism.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. A bale tie buckle having a closed end, sides and straight ends bent inwardly to form the open end of the buckle, the combined length of said bent ends being sufficient to hold them in non-aligning overlapping position after the strain has been applied and the buckle's sides have been drawn into parallelism.
2. A bale tie buckle formed of bent wire having a closed end, an open end, and sides which converge towards each other toward its open end and terminate in inwardly bent

straight ends, said ends being oppositely divergent from the plane of the buckle and bent slightly towards the closed end of the buckle, the overlapping sides of said ends having a total length greater than the distance between the buckle's sides when parallel.

3. A bale tie buckle formed of bent wire having a closed end, side walls which diverge towards said closed end, and inwardly bent free straight ends on the sides forming the open end of the buckle, said ends being elongated sufficiently to produce an overlap initially and throughout the deformation of the buckle responsive to tension from the bale tie which causes its side walls to assume parallelism, the overlapping portions being disposed and adapted positively to hold the free ends out of alignment when the buckle sides are parallel, as and for the purpose described.

In testimony whereof I affix my signature.
JAMES A. TODD.
